UNITED STATES PATENT OFFICE.

WALLACE L. CLAY, OF THE UNITED STATES ARMY.

TRACER AND INCENDIARY BULLET.

1,333,834.

Specification of Letters Patent. Patented Mar. 16, 1920.

Application filed November 18, 1918. Serial No. 263,048.

(FILED UNDER THE ACT OF MARCH 3, 1883, 22 STAT. L., 625.)

To all whom it may concern:

Be it known that I, WALLACE L. CLAY, lieutenant colonel, Ordnance Dept., United States Army, a citizen of the United States, 5 stationed at Frankford Arsenal, have invented an Improvement in Tracer and Incendiary Bullets, of which the following is a specification.

The invention described herein may be 10 used by the Government, or any of its officers or employees in prosecution of work for the Government, or by any other person in the United States, without payment of any royalty thereon.

15 This invention relates to devices commonly known as combined tracer, armor piercing and incendiary bullets or projectiles, whereby a gunner is enabled to so aim or adjust a firearm as to accurately place 20 future shots, if required, and has for one of its objects to provide a device of this character adapted to be projected from a firearm and capable of emitting a pencil of visible vapor by day or a pencil of light by night 25 to denote the line of flight, and to pierce the objective and emit a cloud of vapor by day or a flash of light at night to indicate that the projectile has reached the objective, and likewise to produce a conflagration or an explosion 30 of the contents of the objective.

Another object of the invention is to provide a device of this character having means whereby the vapor and light-producing element and the conflagration element are protected during the flight of the projectile.

With these and other objects in view the invention consists in certain new and useful improvements hereinafter described and 35 specifically set forth in the claims, and in 40 the drawings illustrative of the preferred embodiment of the invention—

Figure 1 is a longitudinal section of the projectile complete.

Fig. 2 is a longitudinal section of the 45 jacket or envelop.

Fig. 3 is a longitudinal section of the soft metal or "lubricating" member in "blank" ready to be forced into the jacket or shell.

Fig. 4 is a longitudinal section of the 50 receptacle for the tracer composition.

Fig. 5 is a sectional detail illustrating a modification in the construction.

The improved device comprises a slug or

core 10 of armor piercing metal such as 55 solid steel, pointed at the forward end and inclosed in a jacket or shell 11. The shell is pointed at the forward end and is preferably of a metal or metallic compound which will be fractured or shattered by impact with a resisting body such as armor 60 plate, engine casings, or other resisting material.

The outer jacket or shell is preferably 65 formed of cupro-nickel, gilding metal, cupro-nickel steel, or the like, but may be of copper clad steel when the projectile is employed for certain purposes or under certain conditions.

The slug 10 is generally smaller in diameter than the interior of the shell 11 and is 70 spaced at its forward pointed end farther from the forward end of the jacket than at the sides, with its rear blunt end terminating intermediate the shell, as shown in Fig. 1. The space between the slug and shell is 75 filled with a mass of relatively soft metal or metallic compound 12, such as lead, a compound of lead and antimony, or lead and tin, or other suitable compound which will be disintegrated when the projectile strikes 80 its objective.

By spacing the "nose" of the slug from the "nose" of the shell, a relatively large portion of the soft metal lubricant or cushion 12 is located in advance of the slug, 85 the advantage and object to be hereafter explained.

Disposed within the shell 10 rearwardly of the slug is a receptacle 13 for the tracer mixture or compound, indicated at 14. The 90 rear end of the receptacle 13 is open and is secured in position by "crimping" the rear edge of the shell inwardly, as shown.

At its rear end the shell 13 is initially reduced or internally tapered as shown in 95 Fig. 2 to facilitate the crimping operation.

The receptacle 13 bears at its closed inner end against the rear end of the slug, as shown in Fig. 1.

The "lubricating" member 12 is cast 100 initially as shown in Fig. 3 and placed within the jacket and pressed therein by a suitable implement to cause it to assume the shape shown in Fig. 1. The slug 10 is then inserted, the receptacle 13 disposed within the 105 jacket rearwardly of the slug and bearing

by its closed inner end against the rear end of the same, and the rear end of the shell "crimped" over the receptacle.

The "charge" of the tracer mixture 14 5 may be deposited within the receptacle before or after it is disposed within the shell, as may be preferred.

The action of the projectile is as follows: When the cartridge is fired, the flame from 10 the propelling powder ignites the tracer composition, which burns throughout the flight of the projectile approximately 300 or 400 yards or longer, depending upon the tracer composition used. Upon impact with 15 the enemy's armor plate, engine parts, or any other resisting material, the projectile jacket is shattered while the steel plug with its alloy lubricant causes penetration.

The "lubricating" substance 12 may be 20 extended over the nose and sides of the slug 10 as shown in Fig. 1, or over the nose only as shown in Fig. 5.

Having thus described the invention what is claimed as new and desired to secure by 25 Letters Patent is:

1. A projectile of the class described comprising a shell of a material fracturable by impact, an armor piercing slug within the shell, a mass of relatively soft metallic substance between the slug and the shell, and a receptacle within the shell rearwardly of the slug, said receptacle containing a substance for producing visible vapor and a flash of light.

2. A projectile of the class described, comprising a shell of a material fracturable by impact, an armor piercing slug within the shell, a mass of relatively soft metallic substance between the slug and the shell, a re-

ceptacle within the shell rearwardly of the 40 slug, said receptacle containing a substance for producing visible vapor and a flash of light, and means for holding the receptacle within the shell.

3. A projectile of the class described comprising a shell of a material fracturable by impact, an armor piercing slug within the shell, a mass of relatively soft metallic substance between the slug and the shell, and a receptacle within the shell closed at the 50 inner end and bearing thereby against the slug, said receptacle containing a substance for producing visible vapor and a flash of light.

4. A projectile of the class described comprising an armor piercing slug, a shell externally of the slug of a material fracturable by impact, a mass of relatively soft metallic substance between the slug and the shell, and a receptacle within the shell containing a substance for producing a visible vapor and a flash of light.

5. A projectile of the class described comprising a shell of a material fracturable by impact, an armor piercing slug within the 65 shell, a mass of relatively soft substance between the slug and the shell, and a receptacle containing a vaporizing and inflammable substance.

6. A projectile of the class described comprising a shell fracturable by impact, an armor piercing slug within the shell, a mass of relatively soft metallic substance between the slug and the shell, a receptacle for tracer material within the shell bearing at 70 one end against the slug and retained in place by a crimped portion of said shell.

WALLACE L. CLAY.
